DRESSER OR SIMILAR ARTICLE

William J. Carr, Gardner, Mass., assignor to Heywood-Wakefield Company, Gardner, Mass., a corporation of Massachusetts

Application March 9, 1954, Serial No. 29,429

Term of patent 7 years

(Cl. D33—6)

Fig. 1.

Fig. 1 is a front perspective view of a dresser or similar article showing my new design, and Fig. 2 is a fragmentary sectional view on the line 2—2 of Fig. 1 but on a scale larger than that of Fig. 1.

The dominant feature of the design resides in the portion shown in full lines, the design being particularly characterized by the configuration of the drawer fronts in association with the tiered drawer compartments.

I claim:

The ornamental design for a dresser or similar article, substantially as shown and described.
